UNITED STATES PATENT OFFICE.

WILLIAM BRAJDODICS, OF SHARPSVILLE, PENNSYLVANIA.

STREET-CLEANER.

1,273,998.

Specification of Letters Patent. Patented July 30, 1918.

Application filed March 18, 1918. Serial No. 223,152.

To all whom it may concern:

Be it known that I, WILLIAM BRAJDODICS, a subject of the King of Hungary, residing at Sharpsville, in the county of Mercer and State of Pennsylvania, have invented certain new and useful Improvements in Street-Cleaners, of which the following is a specification.

The primary object of the invention is the provision of a street cleaning appliance adapted for use upon dusty thoroughfares whereby the sweepings are rapidly collected without agitating the dust and are positioned for carting away to a desirable location.

15 A further object of the invention is the provision of a street cleaner arranged for sweeping large areas with great rapidity and without agitating the dust from the refuse being collected, thereby rendering the 20 device sanitary for employment in thickly populated communities.

25 A still further object of the invention is to provide a street cleaning machine adapted for easily and quickly performing the services of a large number of laborers in sweeping a street in a dustless manner, the operation of sweeping and collecting refuse being expeditiously accomplished by a single traveling of the machine over the surface to be 30 cleaned.

In the drawings forming a part of this application and in which like numerals refer to corresponding parts throughout the several views:

35 Figure 1 is a side elevation of the device; Fig. 2 is a top plan view thereof;

Fig. 3 is a vertical transverse sectional view of the same taken upon line 3-3 of Fig. 1;

40 Fig. 4 is a detail vertical transverse sectional view taken upon line 4-4 of Fig. 1;

Fig. 5 is a horizontal sectional view showing the sweeping brush and its operating means in top plan with parts broken away;

45 Fig. 6 is an enlarged detail sectional view taken upon line 6-6 of Fig. 1; and

Fig. 7 is a sectional view of an operating hub portion of the device.

Referring more in detail to the drawings, 50 my device is in the form of a vehicle having a platform 10 mounted upon rear wheels 11 and front wheels 12, the device being adapted to be drawn forwardly over the roadway 13 by attaching suitable draft means, not 55 shown, to the tongue 14 of the vehicle, a

suitable driver seat 15 being forwardly positioned upon the said platform 10.

An axle 16 is secured to the rear wheels 11 and journaled through a bolster 17 carried beneath the rear portion of the platform 11 while a gear 18 and sprocket-wheel 19 are secured upon the said axle 16 adjacent its opposite ends and inwardly of the wheels 11. A casing 20 of inverted V-shaped form in longitudinal section is carried by 60 the platform 10 having its forwardly inclined portion 21 extending through the said platform with an open end or mouth 22 substantially vertically positioned therebeneath and with its rearwardly inclined portion 23 65 extending rearwardly of the platform 10 with a closing slide 24 at its open rear end or outlet 25 adapted to be opened by means of a lever 26.

An endless apron 27 is arranged within 70 the bottom of the front portion 21 of the casing 20 for taking up the sweepings at a point adjacent the mouth 22 and carrying the same upwardly in the casing portion 21 for depositing the sweepings in the rear portion 23 thereof. The apron 27 or conveyer-belt has an operating shaft 28 journaled through the lower front end of the casing portion 21 with a sprocket-wheel 29 upon each end of the shaft 28 for accommodating 80 sprocket-chains 30 running over the wheels 29 and similar sprocket-wheels 31 carried by shafts 32 arranged above the rear axle 16 provided with gears 33 in constant mesh with the axle-gears 18. It will be understood that 90 the conveyer 27 will be operated by this manner of connections between the shaft 28 and the axle 16 so as to transfer to the collecting portion 23 of the casing 20 any sweepings which are placed upon the belt 27 during the 95 forward travel of the machine.

Oppositely arranged brackets 34 are arranged beneath the platform 10 adjacent the opposite sides thereof and forwardly of the casing 20 having upright screws 35 freely 100 extending through bottom openings 36 in the said brackets, the axle or spindle 37 of a sweeping brush 38 being journaled in the lower ends of the said screws 35. Sprocket wheels 39 are threaded upon each of the 105 screws 35, the said wheels being in the form of turn-nuts mounted upon the bottom or cross-piece 40 of each of the brackets, an operating chain 41 being arranged over the said wheels 39.

A stub-shaft 42 is centrally positioned beneath the platform 10 having a sprocket-wheel 43 positioned between the opposite plies of the chain 41 and in mesh with each 5 of the same while a sprocket-wheel 44 arranged upon the stub-shaft 42 is operated by a sprocket-chain 45 through the agency of a turn-post 46 so that the screws 35 may be rotated in either desired direction by 10 turning the hand-wheel 47 with which the upper end of the post 46 is provided. In this manner, the brush 38 may be elevated or lowered at the will of the operator by turning the said hand-wheel 47 which it will 15 be noted is located adjacent the driver seat 15 of the machine. Sprocket-wheels 48 are secured at the opposite ends of the brush spindle 37 having sprocket-chains 49 running thereover and also over the afore- 20 mentioned sprocket-wheels 19 carried by the rear axle 16. The forward travel of the machine is adapted in this manner to revolve the brush 38 for sweeping the roadway 13 and forcing the sweepings into the adjac- 25 ently positioned open mouth 22 of the casing portion 21 and upon the endless conveyer 27. A scraper 50 in the form of a plate is carried by the upper forward edge of the casing portion 21 adapted for contact 30 by the brush 38 during the sweeping operation to insure the passing of all of the sweepings into the casing mouth 22.

A tank 51 is mounted upon the platform 10 above the brush 38 adapted for holding 35 a suitable fluid to be sprinkled onto the surface to be operated upon by the brush 38, a suitable hollow plate 52 being arranged for this purpose transversely beneath the platform 10 with an elongated perforated 40 nozzle 53 rearwardly inclined toward the surface of the roadbed 13 immediately in front of the brush 38. A controlling valve 54 for the fluid-dispensing plate 52 has an operating member 55 connected with a lever

56 positioned for actuation adjacent the 45 driver-seat 15. A suitable lid 57 is provided for the tank 51 and it will be understood that any form of fluid such as water or a germicide may be provided in the tank for use in sprinkling the roadbed 13 preventing 50 dust from arising during the sweeping operation, thereby rendering the machine sanitary.

What I claim as new is:—

1. A street-cleaning device comprising a 55 vehicle, a refuse-collecting casing carried by the vehicle, oppositely positioned brackets carried by the vehicle, a sprocket-wheel in each of said brackets, an upright screw in threaded engagement with each of said 60 wheels, a brush journaled between the lower ends of said screws, operating means for the brush, a sprocket-chain arranged over the said wheels, a post forwardly positioned upon the vehicle, a stub-shaft positioned centrally of the vehicle between the plies of 65 said sprocket-chain, operating connections between the said chain and stub-shaft, operating connections between the said stub-shaft and post, and a hand-wheel upon the top of 70 said post.

2. A device of the class described comprising a vehicle having a platform, opposite brackets depending from the platform, a sweeping brush arranged transversely beneath the platform with its spindle extending beneath said brackets, upright screws freely extending into said brackets with the spindle of the brush journaled in the lower 80 ends of said screws, operating wheels for 85 said screws threaded upon the screws and positioned upon the brackets whereby the brush is adapted to be supported in its vertical adjustable position, and operating means for said wheels adapted for actuation 85 from a point above the platform.

In testimony whereof I affix my signature.
WILLIAM BRAJDOVICS.
